HYDRAULIC THROTTLE CONTROL

Erold F. Pierce, Piney Lake, N. J., assignor to
Wright Aeronautical Corporation, a corpora-
tion of New York

Application September 2, 1939, Serial No. 293,207

15 Claims. (CL 123—103)

This invention relates to engines and is particularly concerned with improvements in control means therefor.

The objects of the invention will be better understood by first briefly outlining the problem which has been solved. In aircraft engines equipped with superchargers and with constant speed propellers, the amount of power delivered is roughly proportional to the manifold pressure in the engine induction system, and, if it be desired to operate at constant power under varying altitude conditions, the manifold pressure must be readjusted from time to time. The prior art provides means for maintaining constant manifold pressure comprising a bellows device communicating with the manifold, which bellows is balanced against an adjustable spring. The bellows controls the engine throttle through a servo-motor so that throttle opening is automatically varied to maintain a balance of the manifold pressure against the spring. Manifold pressure regulators of the prior art have been interconnected with a manual throttle which has not been particularly satisfactory.

Accordingly, it is an object of this invention to provide a manual throttle control in combination with an automatic throttle regulator so arranged and organized that the manual lever may overcontrol the automatic regulator at any time and during such overcontrol will have definite positions of adjustment which correspond to the actual positions of the engine throttle. A further object of the invention is to provide automatic means for connecting the manual throttle in response to actuation thereof, and correspondingly, to disconnect the automatic regulator at such times as the manual throttle is in use, and to reconnect the regulator at such times when the manual throttle is not in use.

A further object of the invention is to provide a hydraulic throttle overcontrolling means which may be coordinated with existing forms of automatic throttle regulators, associated objects being the provision of specific mechanisms which are hereinafter described in detail. For a clearer understanding of the details of the invention, reference may be made to the description below in connection with the drawing, in which,

Fig. 1 is an elevation of an aircraft power plant incorporating the invention, and

Fig. 2 is an enlarged section through an automatic regulator and the control mechanism of the invention.

In Fig. 1, 10 represents an engine crankcase upon which a plurality of cylinders such as 11

are secured, the crankcase including an annular manifold 12 and a blower section 13 upon which a carburetor 14 is mounted, the carburetor including a throttle actuated by a lever 15.

5 To the rear of the blower section is secured an automatic manifold pressure regulator 16, the mechanism of which is shown in detail in the left-hand part of Fig. 2, the regulator being connected through a pipe 17 to the manifold 12. Upon the regulator 16 is mounted a hydraulic motor 18, shown in detail in the right-hand part of Fig. 2, said motor having a piston rod 19 extending from the upper end thereof which is connected to the throttle 15 by a link 20. A piston rod 21 extends from the lower end of the motor 18, this being connected to a conventional throttle lever in the pilot's cockpit through a rod 22, a bellcrank 23, and a link 24.

Referring now to Fig. 2, the regulator 16 comprises a housing within which are serially disposed bellows 26 and 27 separated by a partition 28. The bellows 26 confines a fixed quantity of elastic fluid or may be evacuated while the bellows 27 communicates with the manifold through the opening 29 and the pipe 17. A spring 30 serves to balance the manifold pressure and this spring may be adjusted as to tension by a nut 31 which may if desired be provided with a remote control. The spring 30 may be preset for any desired manifold pressure; if the actual manifold pressure is less than that desired, the partition 28 will move downwardly thus moving an arm 32 with it to actuate a servo-valve 33 slidable in a bore 34. Fluid pressure as from the engine lubricating system is led to the regulator through a passage 36 opening between small pistons 37 and 38 forming part of the valve 33. When, as indicated, the valve 33 is moved downwardly, fluid pressure passes to a port 39, opening another port 40 for drainage through a port 41 to the interior of the housing 16, and thence back to the engine through a drain opening 42.

If the manifold pressure be too high, the valve 33 is moved upwardly connecting the oil pressure supply to the port 40 and connecting the port 39 for drainage.

The hydraulic motor, operated by the regulator 16, comprises a cylinder 44 to which a piston 45 is closely fitted, said piston being connected to the engine throttle through the piston rod 19. A lower piston 46 is also engaged with in the cylinder 44 from which the piston rod 21 extends from the bottom of the motor. Suitable packing and glands 47, 48, and 49, 50 prevent fluid leakage from the cylinder and also guide

the respective piston rods. The piston rod 21 is formed with spaced annular grooves 52 and 53 which register with drillings 54 and 55 in the lower end of the motor connected respectively to the regulator ports 48 and 39. The drilling 54 continues beyond the piston rod 21 as a port 56 opening to the cylinder 44 just above the top surface of the piston 45 when the latter is in its bottom position, and in which position the rod grooves 52 and 53 open the drillings 54 and 55 respectively to the port 56 and to a port 57 leading to the top of the cylinder 44 above the piston 45.

Accordingly, when the piston 45 is in its bottom position, fluid from the regulator 16 may actuate the motor 18 by moving the piston 45 up and down to regulate the throttle 15 and thus adjust manifold pressure so that the regulator 16 will eventually balance.

The motor 18 is provided with a bypass 60 leading from the top of the cylinder 44 to the bottom thereof, the lower opening of said bypass being covered by the piston 46 when same is in bottom position. The piston 46 is provided with a bore 61 closed by a check valve 62, the valve being so disposed that fluid may flow from the top to the bottom of the piston but may not flow from the bottom to the top. The bypass 60 and the check valve 62 provide the means by which the piston rod 21 may be actuated to overcontrol the regulator 16, in the following manner: Let it be assumed that the regulator has positioned the throttle about half opened wherefore the piston 45 is midway of the cylinder as shown. It is desired to manually operate the throttle, so the pilot moves his throttle control to a throttle opening position whereupon the piston 46 moves upwardly and concurrently, the grooves 52 and 53 become misaligned with the regulator passages 54 and 55 to cut off the regulator from the throttle motor. At the same time, the piston uncovers the bypass 60 and that fluid between the pistons 45 and 46 flows through the bypass valve 62 to the cylinder portion below the piston 46, and the pistons 45 and 46 upon continuous movement of the latter, about one another. Thereupon, these pistons are hydraulically locked together so that any movements of the manual throttle rod 22 will communicate to the throttle 15. The hydraulic lock is effective in two ways—first, by suction between the heads of the pistons 45 and 46, and second, by the fixed amount of hydraulic fluid confined above and below the pistons and in the bypass 60. For instance, if the pistons are jointly moved upward, fluid above the piston 45 flows down through the bypass 60 and to the lower part of the cylinder to act upon the lower face of the piston 46, and vice versa.

When it is desired to again allow the regulator 16 to actuate the throttle, the manual throttle rod 22 is moved to a closing position whereupon the throttle 15 is temporarily closed. As the piston reaches its bottom position, the bypass 60 is closed, the passages 54 and 55 are opened to the ports 56 and 57, and fluid entering through the port 56 breaks the seal between the abutting faces of the pistons 45 and 46 whereby the piston 45 may be moved by hydraulic pressure to the appropriate position as governed by the regulator 16.

The arrangement above described allows the pilot to know at a glance the general range of throttle opening when the throttle is under manual control, and allows him to throw the throttle

over to the regulator by manipulation of his throttle lever without the need of bothering with an extra control which was previously necessary to turn off the automatic regulator. The invention also simplifies the control arrangement between the throttle lever, the regulator, and the throttle and allows for transition between automatic and manual throttle operations with a minimum of operating and mechanical complication.

While I have described my invention in detail in its present preferred embodiment, it will be obvious to those skilled in the art, after understanding my invention, that various changes and modifications may be made therein without departing from the spirit or scope thereof. I aim in the appended claims to cover all such modifications and changes.

I claim as my invention:

1. In combination in an engine having a throttle, automatic means for operating the throttle, manual means for operating the throttle, and a connecting device for the throttle and said automatic and manual means comprising a manual means element engageable with an element of the throttle at any time, and operative when so engaged to disconnect the automatic means from the throttle, said manual means when moved to the position of complete throttle closing being disconnected from the throttle and serving to reconnect the automatic means for throttle operation.

2. In an engine having a throttle, automatic throttle adjusting means having a pair of fluid outlets the fluid pressure of which is controlled according to desired throttle opening, a cylinder having a piston including a rod extending from one cylinder end to the throttle, said fluid pressure outlets communicating with the cylinder above and below said piston, a second piston having a rod extending from the other end of the cylinder, manual control means for operating the second piston, a bypass around the first piston covered by the second piston when the latter is in a throttle closing attitude, and a check valve in the second piston head permitting its advance toward the first piston but preventing separation of the pistons thereafter until the manual control means is moved to a throttle closing position whereat fluid from said automatic device enters between said pistons to thereafter afford automatic throttle operation.

3. In an engine having a throttle, automatic throttle adjusting means having a pair of fluid outlets the fluid pressure of which is controlled according to desired throttle opening, a cylinder having a piston including a rod extending from one cylinder end to the throttle, said fluid pressure outlets communicating with the cylinder above and below said piston, a second piston having a rod extending from the other end of the cylinder, manual control means for operating the second piston, a bypass around the first piston covered by the second piston when the latter is in a throttle closing attitude, a check valve in the second piston head permitting its advance toward the first piston but preventing separation of the pistons thereafter until the manual control means is moved to a throttle closing position whereat fluid from said automatic device enters between said pistons to thereafter afford automatic throttle operation, and valve means in the fluid passages for said automatic adjusting means for isolating the means from said cylinder,

responsive to movement of the manual control means from the throttle closing position.

4. In a powerplant, a throttle, automatic means for adjusting the position of the throttle, manual throttle adjusting means, and means responsive to movement thereof from a datum for disconnecting said automatic means from the throttle and for connecting said manual means to the throttle and responsive to return of the manual means to the datum for disconnecting the manual means from and for reconnecting the automatic means to the throttle.

5. In a powerplant, a throttle, automatic means for adjusting the position of the throttle, manual throttle adjusting means, and means responsive to actuation thereof from a certain position for disconnecting said automatic means from the throttle to allow of full manually controlled throttle movement both greater and less than the movement called for by the automatic means, said automatic means being reconnected for throttle operation upon movement of said manual means to said certain position.

6. In a powerplant, a throttle, automatic throttle adjusting means, and a manual throttle overcontrol which when actuated disconnects said automatic means from throttle operation and connects to the throttle for manual operation thereof.

7. In a powerplant, a throttle, manifold pressure responsive means for hydraulically adjusting the throttle to maintain a preset manifold pressure; said means comprising a manifold pressure actuated servo valve and a hydraulic motor controlled thereby; and a manually adjustable mechanism comprising a valve movable to close the hydraulic connection from the servo valve to the motor, and means including a hydraulic coupling for actuating the throttle during such closure.

8. A throttle control device comprising a cylinder having opposed stemmed pistons, a dual shutoff valve embodied in the stem of the lower piston, conduits from said dual valve to opposite ends of the cylinder, a bypass between opposite cylinder ends closable by said lower piston when adjacent the lower cylinder end, and a check valve in said lower piston preventing flow therethrough in an upward direction whereby the upper piston is forced to move downward when the lower piston is moved downward.

9. A throttle control device comprising a cylinder having opposed stemmed pistons, a dual shutoff valve embodied in the stem of the lower piston, conduits from said dual valve to opposite ends of the cylinder, a bypass between opposite cylinder ends closable by said lower piston when adjacent the lower cylinder end, a check valve in said lower piston preventing flow therethrough in an upward direction whereby the upper piston is forced to move downward when the lower piston is moved downward, and fluid pressure means leading to said dual shutoff valve, said fluid pressure being operative, when said dual valve is open and the lower piston bottomed, to actuate the upper piston independently of the lower.

10. In a power plant, a throttle, manual adjusting means therefor having one inactive posi-

tion and a plurality of active positions, automatic throttle adjusting means operable when active to adjust the throttle to all of its operating positions, mechanism connecting the throttle to said manual adjusting means in all active positions of the latter and disconnecting the throttle from said manual adjusting means in its inactive position, and mechanism to connect the throttle to said automatic means in response to movement of said manual adjusting means to said one inactive position.

11. In an engine in combination, automatic means to regulate engine power to a presettable value, manually adjustable means to regulate engine power, and mechanism operated by said manual means to selectively connect the automatic means or the manual means for operation through their full ranges of adjustment to the exclusion of the other means.

12. In an engine having an induction manifold in combination, means responsive to manifold pressure to control the manifold pressure to a presettable value, manually controllable means to vary manifold pressure, said two means being operable independently of one another, and mechanism to connect one means for operation to the exclusion of the other means.

13. In an engine having an induction manifold in combination, means responsive to manifold pressure to control the manifold pressure to a presettable value, manually controllable means to vary manifold pressure, said two means being operable independently of one another, and mechanism to connect one means for operation to the exclusion of the other means, said mechanism being operable to effect said connections in response to placement of said manually controllable means in a certain position of adjustment thereof.

14. In an engine having an induction manifold in combination, means responsive to manifold pressure to control the manifold pressure to a presettable value, manually controllable means to vary manifold pressure, said two means being operable independently of one another, and mechanism to connect one means for operation to the exclusion of the other means, said mechanism being operable to connect the automatic means for operation when the manual means is set for low power or idling operation and being operable to disconnect the automatic means from operation upon setting of the manual means for increasing power operation.

15. In an engine in combination, a power regulator, automatic means to regulate engine power to a selectable value, manually operable means to regulate engine power to any available amount, said manually operable means having one inactive position, and means; actuated by movement of said manual means to said inactive position to connect the automatic means to said power regulator and to disconnect the manual means therefrom; and actuated by movement of said manual means from said inactive position to disconnect the automatic means from said power regulator and to connect the manual means thereto.
